UNITED STATES PATENT OFFICE.

HERBERT AKROYD STUART, OF PERTH, WESTERN AUSTRALIA,
AUSTRALIA.

INTERNAL-COMBUSTION ENGINE.

No. 845,140.

Specification of Letters Patent.

Patented Feb. 26, 1907.

Application filed December 2, 1905. Serial No. 289,989.

To all whom it may concern:

Be it known that I, HERBERT AKROYD STUART, M. I. Mech. E., a subject of the King of Great Britain, residing at Akroyd Buildings, Melbourne Road, Perth, Western Australia, Australia, have invented new and useful Improvements in Internal-Combustion Engines, of which the following is a specification.

10 This invention relates to improvements in internal-combustion or explosion engines of the kind forming the subject-matter of British Letters Patent No. 15,994 of 1890, and has reference more particularly to the manner in which the combustible mixture is formed. In engines of this class as heretofore constructed a quantity of air considerably in excess of that necessary for the proper combustion of the hydrocarbon vapor produced in the vaporizer is drawn into the cylinder.

25 The object of my invention is to utilize this air or a large portion thereof for purposes of combustion, so as to obtain a greater mean pressure than heretofore, and therefore an increase of power developed.

According to the present invention a vaporizer and cylinder of similar construction to those described in the specification of British Letters Patent No. 15,994 of 1890 are utilized; but instead of injecting the charge of oil or other fuel into the heated vaporizer only a further supply of oil or other fuel is introduced into the cylinder and mixes with 35 the air or other gas therein, while a body of air is always provided next or near to the neck of the vaporizer. In some cases also water spray or vapor or the like may be mixed with the fuel.

40 To enable my invention to be fully understood, I will describe the same by reference to the accompanying drawings, in which—

Figure 1 is a sectional elevation of so much of an explosion-engine as is necessary to illustrate my invention. Fig. 2 is a longitudinal section of the same. Fig. 3 is a horizontal section of a cylinder. Fig. 4 is a section on the line 4 4, Fig. 1. Fig. 5 is a view similar to Fig. 4, illustrating a modification of the 50 invention. Fig. 6 is a section on the line 6 6, Fig. 5.

a is the cylinder, and *b* the vaporizer, which are connected by a contracted neck *c* in the manner described in the specification

of the said former patent, the said cylinder 55 and the contracted neck being water-jacketed.

d is a pump of any desirable construction which serves for drawing liquid hydrocarbon from a reservoir *e* and delivering it through a pipe *f* into the vaporizer *b*, and *g* is another 60 pump also drawing from the reservoir *e*, delivering through the pipe *h* and the passage *i* directly into the cylinder, as clearly shown in Fig. 2.

j is a trunk-piston the inner end of which 65 is advantageously recessed, as indicated at *k*, so as to provide a cavity into which the liquid hydrocarbon passing through the passage *i* will enter in a liquid condition, the vaporization taking place during the outward stroke 70 and possibly also during the compression-stroke, the air admitted on the induction-stroke following after the vapor formed or being formed and serving to isolate the same from the vapor formed in the vaporizer *b*. 75 As shown, the piston *j* is provided internally with webs *j'*, which extend across the same. These webs, however, may be arranged in any other suitable manner. In large engines it is advisable to provide for water-cooling 80 the piston.

l is the air-admission valve, which is advantageously arranged, as shown, so that the air will enter through the neck *c*, and *m* is a box containing an exhaust-valve *n*, as indicated in dotted lines in Fig. 2.

o is the usual half-speed shaft, carrying cams *p*, *q*, *r*, and *s* for operating, respectively, the pump *d*, the pump *g*, the air-inlet valve *l*, and the exhaust-valve *n*. The cam *q* for operating the pump *g* is, as shown, formed spirally and is adapted to be moved longitudinally upon the shaft *o* for varying the time of operation of the pump *g* relatively with the pump *d*. 95

t is a centrifugal governor driven by the shaft *o* and working in conjunction with a rod *r'*, having two tappets or pins co-operating with the suction-valves *d'* *g'* of the pumps *d* and *g*, respectively, in such a manner that when the governor attains a certain speed of rotation the said tappets will set against the said valves *g'* *g''* to depress the same so that the charge of oil, which under ordinary circumstances would be injected into the vaporizer 100 and cylinder, will be forced back into the oil-reservoir *e*. The tappet which co-operates with the valve *g'* is preferably made adjustable, as 105

shown, to allow of its striking its valve earlier than the valve d' is struck, so that both charges will not be cut off simultaneously.

In the operation of the engine the liquid hydrocarbon is injected into the cylinder through the passage i when the piston is at or near the end of the instroke, as indicated by dot-and-dash lines in Fig. 3. During the next or suction stroke air which enters through the valve l carries the cylinder charge of vapor forward in the cylinder, so that either pure air or air only slightly diluted with hydrocarbon vapor remains at the back of the cylinder. At the same time a charge of liquid hydrocarbon is injected into the chamber b and vaporized therein. During the next instroke the charge in the cylinder and vaporizer is compressed and the heat augmented to such an extent that when the piston reaches its innermost position a simultaneous or successive automatic ignition takes place in the cylinder and in the vaporizer. The products of combustion are discharged through the exhaust-valve n in the usual manner during the fourth stroke of the cycle, when the operation hereinbefore described is repeated. When it is desired to run the engine light or with light loads, the pump g , supplying the cylinder charge, is put out of action, when the engine will continue to operate with a vaporizer charge only, as described in the specification before referred to. It is sometimes found advisable to vary the times of introducing the two charges of fuel, and this can be effected by varying the position of the cam q upon the shaft o . Also instead of introducing the hydrocarbon directly into the cylinder it may be introduced into the air-passages so as to enter with the air during the first part of the induction-stroke. In some cases the air instead of being admitted through the valve l in the contracted neck c , as hereinbefore described, may be introduced through a special air-inlet valve on the side of the cylinder, a further supply being admitted toward or at the end of the suction-stroke through the valve l , thereby insuring that the air at the neck of the vaporizer is pure and at the same time obtaining a higher degree of compression with the same cylinder clearance than in the arrangement shown in Figs. 1 to 4. This arrangement is illustrated in Figs. 5 and 6, wherein u indicates an air-inlet valve arranged adjacent to the exhaust-valve. In this arrangement the air which enters through the valve l is preferably supplied from a chamber v , surrounding the neck c , and which is supplied with compressed air through the pipe w from a pump upon the engine.

Although in the foregoing description I have referred to the oil as being introduced by means of a pump, it is to be understood that it may be introduced by means of compressed air or air-suction or in any other suitable manner.

Having now particularly described and ascertained the nature of my said invention and in what manner the same is to be performed, I declare that what I claim is—

1. In an internal-combustion engine provided with a vaporizer in open communication with the working cylinder by a contracted neck the provision of means for injecting charges of hydrocarbon into the vaporizer and into the cylinder and for introducing a layer of air between these charges, substantially as, and for the purpose, described. 70
2. In an internal-combustion engine, the combination with a cylinder, of a vaporizer communicating with said cylinder but separated therefrom by an open passage, separate means for injecting charges of hydrocarbon into said vaporizer and into said cylinder and means for admitting charges of air into said passage between said vaporizer and said cylinder, substantially as described. 80
3. In an internal-combustion engine, the combination with a cylinder, of a vaporizer communicating with said cylinder but separated therefrom by an open passage, separate means for injecting charges of hydrocarbon into said vaporizer and into said cylinder, means for varying the relative time for injecting said charges of hydrocarbon into said vaporizer and said cylinder and means for admitting charges of air into said passage between said vaporizer and said cylinder, substantially as described. 90
4. In an internal-combustion engine, the combination with a cylinder, of a reciprocating piston therein, said piston being provided at its end with a recess, of a vaporizer in communication with said cylinder but separated therefrom by an open neck, means for injecting a charge of hydrocarbon into said vaporizer, separate means for injecting a charge of hydrocarbon into said recess in said piston when near the end of its instroke and means for admitting charges of air into said neck between said vaporizer and said cylinder, substantially as described. 100
5. In an internal-combustion engine, the combination with a cylinder, of a vaporizer communicating with the rear end of said cylinder but separated therefrom by a neck, separate means for injecting charges of hydrocarbon into said vaporizer and into said cylinder, means for admitting charges of air into said neck between said vaporizer and said cylinder and separate means for admitting charges of air into the rear end of said cylinder adjacent to the mouth of said neck, substantially as described. 115
6. In an internal-combustion engine, the combination with a cylinder, of a vaporizer in communication therewith, separate means for injecting charges of air into said vaporizer and into said cylinder, means for introducing a layer of air between said charges in said vaporizer and said cylinder and a governor. 125

adapted to automatically cut off said charges of hydrocarbon from said vaporizer and said cylinder, substantially as described.

7. In an internal-combustion engine, the combination with a cylinder, of a vaporizer in communication therewith, separate means for injecting charges of air into said vaporizer and into said cylinder, means for introducing a layer of air between said charges in said vaporizer and said cylinder, a governor adapted to automatically cut off said charges of

hydrocarbon from said vaporizer and cylinder and means connected with said governor for regulating the relative times for cutting off said charges of hydrocarbon from said vaporizer and said cylinder, substantially as described. 15
